UNITED STATES PATENT OFFICE.

CHARLES JAQUET, OF STRASSBURG-KÖNIGSHOFEN, GERMANY, ASSIGNOR TO THE FIRM OF SCHNEIDER, JAQUET & CIE., G. M. B. H., OF STRASSBURG-KÖNIGSHOFEN, GERMANY.

SEPARATOR.

1,111,261.

Specification of Letters Patent.

Patented Sept. 22, 1914.

Application filed October 26, 1911. Serial No. 656,804.

To all whom it may concern:

Be it known that I, CHARLES JAQUET, a subject of the German Emperor, and residing at Strassburg - Königshofen, Germany, have invented certain new and useful Improvements in Separators, of which the following is a specification.

The present invention has reference to improvements in separators for grain and the like, and relates more particularly to improvements in the means for elastically supporting or suspending the flat separating sieves or screens in such separators.

In order to make this invention more readily understood, I will describe it with reference to the accompanying drawing, in which—

Figures 1, 2 and 3 represent side elevations of several forms of my improved supports with adjacent parts, partly in section. Figs. 1^a, 2^a and 3^a show respectively plan views of these supports.

For supporting the screen boxes of plane-separators with parallel crank action it is now customary to employ rods or spiral springs in rows or in bundles. However, owing to the relatively low capacity of resistance in longitudinal *i. e.* axial direction, the number of such rods must be large, and on the other hand, in the case of springs, though they readily admit of lateral movement, they show the disadvantage that they easily give or extend longitudinally, so that the sifter will execute movements also in this direction, which seriously interferes with smooth operation. The object of this invention is to do away with these drawbacks by using as supports, which may be provided singly or in groups and bundles, twisted or helically wound flat or round bars, whereby owing to the artificial shortening of the individual rods an enhanced rigidity in the direction of the longitudinal axis of the rods is obtained, without the unimpeded horizontal shaking action of the screen being in any way interfered with, and in which instance the number of such rods may also be reduced.

The screen boxes of plane-separators are given a horizontal gyratory motion by means

of eccentric or crank gear, and for this purpose are supported by a number of vibrating or pendulum rods. In the embodiments of my invention illustrated, these supports are in the shape of single flat bars or bundles of rods *a*, helically twisted about their axis. In Fig. 1 there is shown a single such support *a*, secured below to a rigid shoe *b* and above to the vibrating screen box *c*. In Fig. 2 is illustrated a group of such twisted supports, and in Fig. 3 a bundle of them, helically intertwined. For the purpose of enhancing the elasticity of these pendulum rods, the number of twists may be increased toward the middle part of their length. By this twisted formation, which causes an artificial shortening of the individual rods and thereby an enlargement of the cross-sectional area thereof, obviously, a greater elasticity of the rods in lateral direction and an increase of their stability in longitudinal direction is obtained. Such supports, therefore, combine all the advantages of the old supports, without showing any of their disadvantages, and they can, obviously, also be used with separators in which the screens are hung-up.

What I claim is:—

1. In a plane separator, the combination of a base, an upright resilient supporting member consisting of a helically twisted bar with the pitch of the twists decreasing toward the center, the lower end of said supporting member being rigidly secured in and upon the base, and a vibratory screen secured upon the upper end of said supporting member.

2. In plane separators, a composite pendulum support comprising a plurality of elastic members, the support being so twisted about its longitudinal axis that the cross sectional area is practically the same throughout the length of the support, substantially as set forth.

In testimony whereof I affix my signature in presence of two witnesses.

CHARLES JAQUET.
